UNITED STATES PATENT OFFICE.

JOHN W. DE FORD, OF LOS ANGELES, CALIFORNIA.

ATTACHMENT FOR STEAM PRESSING MACHINES.

Application filed September 14, 1926. Serial No. 135,315.

The present invention relates to steam pressing machines, such as are employed for pressing garments, and pertains more particularly to attachments for same.

5 In using such presses it is found that portions of many garments, such as ruffles and the like, do not adapt themselves to the surface of the press and accordingly must be pressed by other means, such as an electric iron. Many materials are particularly suited 10 to be pressed by steam presses, inasmuch as steam is forced through or drawn through the fabric. It is therefore one of the primary objects of this invention to provide 15 efficient and convenient means for pressing such garment portions while making use of certain advantages of the steam.

Another object of the invention is to provide for applying the invention to presses 20 now in use.

My invention contemplates the provision 25 of a simple pressing iron which does not require to be heated by electricity or other additional sources of heat, and it is among 30 the objects of this invention to utilize some of the heat of the steam press to maintain an iron at the desired temperature at all times.

Still other objects and advantages of my 35 invention will appear hereinafter.

I have illustrated my invention by the accompanying drawings, in which:—

Figure 1 is a plan view of a common type 40 of press with my invention applied thereto.

Figure 2 is a view in cross section seen on 45 a line 2—2 of Fig. 1.

Figure 3 is a view in side elevation of the 50 part hereinafter known as the housing, showing said housing as it appears removed from the press.

Figure 4 is a view in longitudinal section 55 of the housing, with an iron in position therein.

Figure 5 is a view similar to Fig. 2, showing 60 a modified construction for the housing.

In the drawing the numeral 8 indicates 65 the movable head of a common type of steam press. Said head includes an upper wall 9 and a lower wall 10 and an intermediate 70 wall 11; said walls providing an upper steam space 12 and a lower steam space 13. The head is usually fixed to a pivoted Y bracket, such as 14, to which are swivelly connected 75 the steam lines 15 for conveying steam to the upper steam space. Said upper steam 80 space, as is well understood by those familiar

with such presses, contains steam at all times. By manipulating a valve 16, common to 85 such presses, steam may be admitted to the lower steam space. Various means are employed whereby the steam passes through a garment which is laid between the stationary board 17 and the pivoted head, but my invention is applicable to all types of steam presses in which the top wall of the head is 90 at all times subjected to the heat of steam contained therebelow.

The head normally assumes an inclined 95 position, except when brought into contiguity with the lower board; various levers and 100 connections (not shown) being commonly employed for moving the head from inclined position to pressing position.

The essence of my invention resides in the provision of a housing 18, partially, or entirely, enclosing a space 19. Said space is bounded at the top by a top wall 18^a of the housing, and at the bottom by the top wall 105 of the head; which top wall is always subjected to steam heat. Obviously any article 110 placed upon the top wall will be heated, and when placed upon the top wall and within the housing, the heat will be confined and caused to uniformly heat the contained article.

The housing may be variously formed and 115 may be either an attachment or an integral part, and in Fig. 1, I have shown the housing as being a detachable part having side walls 18^b and an extension 20, to the top 120 wall of the housing, which extension is held down by the same bolts which hold the head of the Y bracket.

Thus the housing in the form of an attachment is very readily applied to any 125 steam press. For the purpose apparent hereinafter, the longitudinal median line of the housing is disposed at an acute angle with regard to the longitudinal median line 130 of the head, so that when the head is inclined, the said median line of the housing is inclined rearwardly, both with regard to horizontal as well as the vertical planes.

Thereby, an iron, such as 21, which is disposed in the housing, will be held therein at 135 all times by gravity, and the constant movement of the head will not tend to dislodge it.

Said iron is especially designed for this purpose and comprises a comparatively 140 thin body 21^a, to which is attached a special handle 22. The handle is disposed as directly above the body of the iron as conven-

ient, but said handle is provided with a rearwardly directed curve 23. The top wall or covering of the housing is provided, at the entrance end, with a notch 24, the margins 5 of which embrace and center the handle with regard to the casing, thus permitting of placing a removable closure 25 in the open end of the housing. The closure is provided with a horizontal rearwardly projecting handle 30. From the curve 23 the handle extends forwardly in horizontal parallel relation to the body 21^a of the iron 10 to a larger curve 31, from whence the handle turns rearwardly again. 15 As to the use and operation of the parts described; the iron is kept within the housing at all times except when in use. The steam pressure in the jackets is generally maintained to provide a constant temperature, and therefore the temperature of the iron will never rise above the best operating temperature. The iron will always be 20 available and uniformly hot and may be used at any time without fear of scorching 25 the material to which it is applied. Even though the iron is not used for many hours at a time there is no danger of it becoming overheated. The closure at the open end of the housing need not be employed when 30 the iron is in constant use, but during long intervals may be kept in place to prevent chilling, particularly when the steam pressure is allowed to lower.

The housing described is simple and may 35 be made of sheet metal, and so proportioned and provided with bolt holes that it can be quickly applied to standard presses. However, where the invention is applied by a manufacturer of presses, it may be done by 40 casting the housing integral with the press head, as shown in cross section in Fig. 5.

It will be apparent now that I have provided a simple and dependable means for 45 providing a hot iron, and which iron is of such shape and proportions that it may be used to iron materials on the press, where the full advantages of the usual steam and vacuum means may be employed and without resorting to the application of the hot 50 dry pressing conditions peculiar to other irons, and

It will also be apparent that while I have 55 specified certain constructions and arrangements of parts, other constructions and arrangements of parts will readily suggest themselves to the minds of those skilled in the art of pressing, and while I have shown and described specific constructions and arrangements of parts I do not limit myself 60 thereto and may employ other constructions

and arrangements as I desire or as occasion requires without departing from the scope of my invention as set forth in the appended claims.

Having described one practical embodiment of my invention, what I claim is:—

1. In a clothes press, an inclined head provided with a wall enclosing a steam space, a housing above said wall providing a pressing iron receiving space of which such wall 70 forms a boundary; said housing so disposed that the longitudinal axis of said iron receiving space is disposed at an appreciable angle with regard to the longitudinal line of said head.

2. In a clothes press, an inclined head provided with a wall enclosing a steam space, a housing above said wall providing a pressing iron receiving space of which such wall forms a boundary; said housing 80 so disposed that the longitudinal axis of said iron receiving space is disposed at an appreciable angle with regard to the longitudinal line of said head; said housing presenting an opening at the outer extremity 85 of the longitudinal median line of the receiving space, and a closure for such opening.

3. In combination with a steam press of the class described having an exposed heated wall, a housing fitted over said wall; the wall being shaped to removably receive a pressing iron, said housing comprising a top wall and side walls, all closely disposed with regard to the corresponding surfaces of said 90 pressing iron.

4. In combination with a steam press of the class described having an exposed heated wall, a housing fitted over said wall; the wall being shaped to removably receive a 100 pressing iron, said housing comprising a top wall and side walls, all closely disposed with regard to the corresponding surfaces of said pressing iron, and said housing being open at an end for insertion and removal of said iron.

5. In combination with a steam press of the class described having an exposed heated wall, a housing fitted over said wall; the wall being shaped to removably receive a pressing iron, said housing comprising a top wall and side walls, all closely disposed with regard to the corresponding surfaces of said pressing iron, said housing being open at an end for insertion and removal of said 110 iron, and said housing being open at the bottom whereby said iron rests directly on said heated surface.

JOHN W. DE FORD.
